UNITED STATES PATENT OFFICE

141,645

DESIGN FOR AN APPLIQUÉ OR SIMILAR ARTICLE

Hugo Stäubli, Zurich, Switzerland

Application May 26, 1943, Serial No. 110,301

Term of patent 3½ years

(Cl. D3—9)

To all whom it may concern:

Be it known that I, Hugo Stäubli, a citizen of the Confederation of Switzerland, residing at Etzelstrasse 31, Zurich, Canton of Zurich, Confederation of Switzerland, have invented a new, original, and ornamental Design for an Appliqué or Similar Article, of which the following is a specification, reference being had to the accompanying drawing, forming part thereof.

Figure 1 is a front elevational view of an appliqué or similar article showing my new design, and,

I claim:

The ornamental design for an appliqué or similar article, substantially as shown.

HUGO STÄUBLI.
